Robert S. Gregg, Fredericktown, Ohio, assignor to The Gregg Manufacturing Company, Fredericktown, Ohio, a corporation of Ohio

Application September 10, 1951, Serial No. 16,598

Term of patent 14 years

(CL. D48—4)

To all whom it may concern:

Be it known that I, Robert S. Gregg, a citizen of the United States, residing at Fredericktown, in the county of Knox and State of Ohio, have invented a new, original, and ornamental Design for a Wall-Mounted Lamp or Similar Article, of which the following is a specification, reference being had to the accompanying drawing, forming a part thereof.

Fig. 1 is a perspective view of a wall-mounted lamp showing my new design;

Fig. 2 is a top plan view thereof;

Fig. 3 is a side elevational view;

Fig. 4 is a bottom plan view; and

Fig. 5 is a rear elevational view.

I claim:

The ornamental design for a wall-mounted lamp or similar article, substantially as shown.

ROBERT S. GREGG.
